BOBBIN REEL

Wolfgang Hermann, Chicago, Ill., assignor to Charles Weiner, Otto Vogl, Martha Weiner, and Margaret Vogl, all of Chicago, Ill., a copartnership trading as Chicago Printed String Company

Application May 6, 1939, Serial No. 272,066

6 Claims. (Cl. 242—134)

This invention relates to a bobbin reel, and more particularly to a reel adapted for dispensing strands of tape, twine, or similar material.

It is an object of the present invention to provide a reel adapted to hold bobbins or spools of various dimensions within the limits of the holder and in which an automatic braking or locking device is provided, whereby, as soon as tension is relieved on the strand being unwound from the bobbin, the brake will automatically operate to prevent further rotation of the bobbin.

It is a further object to provide a reel in which the braking or locking mechanism may be independent of the bobbin itself although controlled thereby and which will be entirely automatic in its operation immediately that the tension is relieved. The independent braking mechanism provides a reel capable of supporting bobbins of any size, within reasonable limits. The invention provides a brake-control means wherein the brake is positively locked against braking action as long as tension is maintained on the strand being unwound from the bobbin and the brake is completely free from all connection with the tensioning device as soon as the tension on the tape is relieved.

A further object is the provision of a reel of the character described in which the brake is automatically operative in either direction, depending upon the direction and rotation of the reel.

It is also an object to provide a braking device which is dependent solely for its braking operation on the momentum of the bobbin; also, wherein the momentum-controlled brake may be equally effective for automatic operation in either direction.

A further object is the provision of a braking mechanism of the type described, in which the brake is automatically released immediately that tension is applied to the tape.

It is also an object to provide an automatic friction-control reel lock which will positively lock the bobbin in either direction of rotation and which will be of few parts, cheap to manufacture, easy to assemble, and which will not easily get out of order.

Further objects will be apparent from the specification and the appended claims.

In the drawing:

Fig. 1 is a perspective view of one embodiment of the invention and illustrates the tape being drawn from the reel under tension.

Fig. 2 is an axial sectional view through the

embodiment illustrated in Fig. 1 and is taken on the line substantially corresponding to line 2—2 of Fig. 1, the position of the bobbin in the holder being shown in dotted lines.

Fig. 3 is a vertical sectional view taken on a line substantially corresponding to line 3—3 of Fig. 2 with the bobbin removed.

Fig. 4 is a fragmentary perspective view of one type of bobbin adapted for use in the bobbin-holder illustrated.

Fig. 5 is a detail sectional view of a slightly different embodiment of friction-tensioning means.

Referring to the drawing in detail, the embodiment illustrated comprises a base 1 having uprights 2 and 3 thereon between which is supported a removable bobbin 4. The bobbin may be of any of the usual types, preferably having end discs 5, as shown in Fig. 4, each of which are provided with a central axial opening 7 and a plurality of small openings 8 which latter are adapted to be engaged by pins 9 (Fig. 2) on a brake disc 10. The brake disc is rigidly secured to a stub shaft 11 having an inwardly extending portion 11a adapted to enter the opening 7 in the bobbin disc 5. The stub shaft 11 is rotatably mounted in the upright 3 and is provided with a slot 12, by which it is retained in a suitable bearing in the upright 3 by means of a screw 13, the end of which is adapted to enter the slot 12.

Although in the present embodiment the pins 9 have been shown for engagement in corresponding openings 8 of the bobbin, it will be apparent that any suitable means for engaging the bobbin may be provided whereby the bobbin may be removably mounted and at the same time will rotate the disc 10 whenever tension is applied to the tape 14.

The upright 2 on the base 1 is provided at its upper end with a slidably shaft 15 which is mounted in axial alignment with the stub shaft 11 and provided with a small flange 16 and a forwardly extending portion which latter is adapted to enter the corresponding opening 7 in the opposite end of the reel 4.

The shaft 15 is provided with a knurled handle 17 and is secured in any adjusted position in the upright 2 by means of a thumb screw 18. The thumb screw is adapted to secure the shaft in any adjusted position so that bobbins of various lengths as well as diameters may be rotatably supported.

A yoke or bridle 19 is provided with inwardly

55 55

extending arms 20 and 21 which arms are pivoted at 22 adjacent the rear of the base. The front or closed end of the yoke is provided with a wire 23 secured thereto in a manner to provide an 5 elongated slot 24, through which the tape or string 14 extends.

The yoke 19 normally rests on the base 1, as shown by dotted lines in Fig. 3. It will be 10 apparent that when tension is applied to the tape 14, the yoke will be raised to the full line position, as shown in Figs. 1 and 3.

The arm 20 of the yoke 19 is provided with an inwardly extending pin 25, which, when the yoke is in raised position shown by full lines, 15 is adapted to engage in the apex of a V-shaped slot 26 in the downwardly extending end of a brake-arm 27 which latter is pivoted to the support 3 at 28. The brake-arm 27 extends upwardly, as shown in Fig. 2, and is provided with 20 an opening 29 in axial alignment with the shaft 11 for the purpose of providing clearance around the shaft so that the brake-arm may oscillate on its pivot 28.

The brake-arm 27 extends upwardly to the 25 top of the brake disc 10 and is provided with laterally spaced inturned brake shoes or locking members 30 which extend over the top of the brake disc 10 and normally provide clearance therebetween as long as tension is applied to the 30 tape.

It will be apparent that as long as the yoke 19 is held in raised position by the tension of the tape 14, the brake-arm 24 will be held vertically centered in the axial plane of the device 35 and the bobbin will be free to rotate with the application of tension to the tape.

The upper end of the brake-arm 27 is provided with a comparatively small friction disc 31, which, in the present embodiment, comprises a 40 small fibre button having a reduced portion 32 for engagement in a corresponding opening in the brake lever. This friction button normally bears against the outer face of the brake-disc 10 and tends to move the brake-lever in the direction 45 of rotation of the bobbin.

In order to retain the upper end of the lever at all times in frictional engagement with the brake disc 10, a small plunger 33 is slidably mounted on the upper end of the support 3 and is urged toward the brake arm by means of a 50 spring 34.

Another embodiment of this pressure means is illustrated in Fig. 5 and comprises a steel ball 55 urged against the disc by means of the tape 36.

The operation of the device is as follows:

Any suitable bobbin of any length or diameter within the limits of the reel-holder may be inserted in the device by loosening the thumb screw 60 and mounting the bobbin between the stub shaft 11 and the slidable shaft 15 and securing the bobbin in place by means of the thumb screw 18. The tape 14 is then passed through the elongated slot 24 and as soon as tension is applied 65 to the tape the yoke 19 will be raised so that the pin 25 engages the apex of the V-shaped slot 26 in the brake arm and the brake arm will then remain centered with the brake shoes 30 free from the brake disc 10 as long as 70 the tension is applied to the tape 14. As soon as this tension is relieved, the yoke 19 will drop to the dotted line position shown in Fig. 3, thus releasing the brake arm 27 and allowing the momentum of the spool and the friction of the 75 button 31 against the disc 10 to move one or

the other of the brake shoes 30 against the edge of the disc, whereby the disc 10 and bobbin 4 secured thereon will immediately be locked against rotation in one direction. If, for any reason, the bobbin is then rotated in the other 5 direction, the friction disc 31 moves the brake lever in the opposite direction and the disc is immediately locked against rotation by the opposite brake shoe 30.

The present embodiment is particularly adapted 10 for use as a reel for tape. However, in the claims the term strand is used and is intended to mean tape, twine, or any similar material for which the invention is adapted.

Modifications may be made by those skilled 15 in the art without departing from the spirit of invention. It is therefore desired that the invention be limited only by the prior art and the scope of the appended claims.

Having thus described this invention, what is 20 claimed and desired to be secured by Letters Patent is:

1. In a bobbin reel, a disc rotatable with a bobbin supported in said reel, an oscillatable brake lever pivoted eccentrically of said disc and 25 having its free end overhanging said disc, frictional means cooperating between said lever and said disc and tending to move said lever to cause braking engagement of said free end with said disc by rotary movement of said disc, and means 30 controlled by the tension of a strand being unwound from said bobbin to prevent said braking movement of said lever.

2. In a bobbin reel rotatable by strand tension, a brake disc rotatable with said bobbin, 35 means eccentrically pivoted with respect to said disc and having a portion engageable with said disc to lock said disc against rotation in at least one direction, means tending to cause locking engagement of said portion with said disc when 40 said bobbin is rotated, and separate means automatically controlled by applied strand tension to interlock with said pivoted means and make said locking means ineffective until said tension is relieved.

3. A bobbin reel comprising a base, a rotatable disc supported thereon, means for supporting a bobbin in driving relation thereto, a lever pivoted eccentrically of said disc and having a brake shoe overhanging the opposite edge of said disc 50 for braking engagement therewith by movement of said lever, means cooperating with said disc and lever and tending to rotate said lever into braking position when said bobbin is rotated in strand unwinding direction whereby to cause said 55 braking engagement, a bridle pivoted for swinging movement on said base and adapted to be raised by tension applied to a strand being unwound from said bobbin, and means on said bridle arranged to cause said lever and shoe to assume a non-braking position when said tension is applied and to enable the momentum of said bobbin to cause said braking engagement when said tension is relieved.

4. A bobbin reel comprising a base, a rotatable disc supported thereon, means for supporting a bobbin in driving relation to said disc, a lever pivoted eccentrically of said disc and having a pair of spaced brake shoes overhanging the opposite edge of said disc but slightly spaced therefrom when said lever is centered substantially on the axial plane of said disc, means tending to move said lever into braking position when said disc is rotated in either direction, the opposite end of said lever having a substantially 70 75

- V-shaped notch therein, a substantially bail-shaped bridle pivoted for swinging movement on said base and adapted to be raised by tension applied to a strand being unwound from said 5 bobbin, and means on said bridle arranged to cooperate with said notch to center said lever when strand tension is applied and to release said lever for braking operation when said tension is released.
- 10 5. In a bobbin reel, a disc rotatable with a bobbin supported in said reel, friction means associated with said disc and having a limited lateral movement by rotary movement of said bobbin in either direction, and additional means 15 controlled by the movement of said friction means in either direction to lock said bobbin against rotation in the same direction, and means operable by applied strand tension to make said locking means ineffective as long as said tension is applied.
6. In a bobbin reel, a frame having means for supporting a bobbin, a member rotatable with said bobbin, a lever pivoted for free movement on said frame and having its free end normally in frictional engagement with said member for limited movement of said free end in the direction of rotation of said member, means on said 10 lever to prevent further rotation of said member after a limited movement thereof in either direction, and means operable by the tension of a strand being unwound to position said lever to enable free rotation of said member as long as 15 said tension is applied.
